(57) CLAIM

The ornamental design for a wine bottle greeting card, as shown and described.

DESCRIPTION

FIG. 1 is a perspective view of a first embodiment of the wine bottle greeting card of the present invention, in a closed position.

FIG. 2 is a front view of the wine bottle greeting card of FIG. 1.

FIG. 3 is a rear view of the wine bottle greeting card of FIG. 1.

FIG. 4 is a right side view of the wine bottle greeting card of FIG. 1.

FIG. 5 is a left side view of the wine bottle greeting card of FIG. 1.

FIG. 6 is a top view of the wine bottle greeting card of FIG. 1.

FIG. 7 is a bottom view of the wine bottle greeting card of FIG. 1.

FIG. 8 is a perspective view of the wine bottle greeting card of FIG. 1, in an open position.

FIG. 9 is a perspective view of a second embodiment of the wine bottle greeting card of the present invention, in a closed position.

FIG. 10 is a front view of the wine bottle greeting card of FIG. 9.

FIG. 11 is a rear view of the wine bottle greeting card of FIG. 9.

FIG. 12 is a right side view of the wine bottle greeting card of FIG. 9.

FIG. 13 is a left side view of the wine bottle greeting card of FIG. 9.

FIG. 14 is a top view of the wine bottle greeting card of FIG. 9.

FIG. 15 is a bottom view of the wine bottle greeting card of FIG. 9; and,

FIG. 16 is a perspective view of the wine bottle greeting card of FIG. 9, in an open position.
